UNITED STATES PATENT OFFICE

106,163

DESIGN FOR A POTENTIAL CELL

Joseph S. Williams, Indianapolis, Ind., assignor
to P. R. Mallory & Co. Inc., Indianapolis, Ind.,
a corporation of Delaware

Application August 7, 1936, Serial No. 64,284

Term of patent 14 years

To all whom it may concern:

Be it known that I, Joseph S. Williams, a citizen of the United States, residing at Indianapolis, in the county of Marion and State of Indiana, have invented a new, original, and ornamental Design for a Potential Cell, of which the following is a specification, reference being had to the accompanying drawing, forming part thereof.

Figure 1 is a perspective view of a potential cell, showing my new design;

Figure 2 is a side view thereof; and
Figure 3 is a bottom view thereof.

What is claimed is:

The ornamental design for a potential cell,
substantially as shown.

JOSEPH S. WILLIAMS.
